UNITED STATES PATENT OFFICE.

MILTON L. DODGE, OF NEWBURYPORT, MASSACHUSETTS.

METHOD OF MAKING TURN SHOES.

Application filed January 7, 1924. Serial No. 684,699.

Turn shoes are now commonly manufactured under what is known as the string system in which the various operations are divided among several operatives, each of whom performs one operation, or if the operations are minor, two or three, and then passes the shoe to the next operator in the proper sequence.

The shoe sole must be in temper when first tacked to the last and must remain so until after the final sole shaping operations have been performed thereon, which commonly is not until a considerable number of other operations have also been performed. This causes a considerable time interval to elapse between the first and last operations in which the sole must be in temper, often as much as an hour and a half being expended in these intermediate operations and in passing from one operative to the next so that this time elapses between the sole tacking operation and the time when the shoe may be permitted to dry out. It has been found impracticable to retemper the soles of shoes which have once become dry, as this injures the upper and is quite likely to stain the linings, and consequently shoes, the assembling of which on the last has been commenced, must be carried through the operations until such time as the temper of the sole is no longer required as soon as possible so that they may still be in temper for the final operation requiring it. They can not be left over night when in any intermediate state as they would not remain that long in temper and would be unsuitable for carrying out the required operations on the soles on the succeeding day. From this it results that the operator who pounds out the soles must wait until the shoes begin to reach him after all the previous operations from the sole tacking have been effected the same day, that is, if the sole tacker starts to work at 8 o'clock a. m. there may be nothing for the pounder out to do before 9:30 o'clock. Likewise the sole tacker must stop work early in order that the last operation requiring the sole to be in temper may be completed on all the shoes which the sole tacker has worked upon that day by the end of the same working day. Moreover, as some of the later operations require a longer time than the earlier ones, the sole tacker must stop work earlier than the pounder out by a greater time interval than his earlier start in the morning. It is not uncommon, there-

fore, for the sole tacker to stop work at from 2:30 to 3 p. m. in order to permit the operators performing the later operations which must be performed the same day to finish their work by 5 o'clock.

Difficulty has also been experienced when any one of the operators performing operations requiring the sole to be in temper is absent, since if he can not be replaced at once all of the other operatives within this group can not work. This will be evident when it is considered that it would not do for those performing operations prior to the absent operator to do their parts as the shoes would then dry out after being partly completed and would be unfit for the later operations, and there is no work left over from the previous day in condition for performing the later operations.

Heretofore, also, when the shoes are being dried they are still on the lasts over which they have been drawn in the relasting operation so that the air does not have free access to the interior of the shoes. It commonly requires as much as five days from the time of relasting for the shoes to become sufficiently dry for the lasts to be removed, and consequently a very large number of lasts is required.

According to the present invention the number of operations which it is necessary to perform while the sole is in temper is much reduced, reducing the time interval between the first and the last to less than one half hour and the time required for each is substantially equalized. The comparatively short time required causes the temper of the sole to be more uniform for the different operations requiring it and permits a longer working day for the individual operator without lengthening the operating time of the factory. This results in a greater output of finished shoes with the same factory equipment and personnel, more efficient operation of machinery and reduced overhead expense. Moreover, the relatively few operations required to be performed while the sole is in temper greatly lessens the chance for the absence of one operator stopping the work of others and decreases the number of others who are affected in case one should be absent.

Moreover, as will later more fully appear, in carrying out the method of this invention, the soles are shaped quickly by machine without requiring special skill on the part

of the operator and to a more perfect form than can be produced by the hand pounding out method which requires considerable skill and a much greater expenditure of time.

5 Further advantages will appear from a more complete description of the method with relation to the accompanying drawings in which

Figure 1 illustrates the shoe as assembled 10 on the last.

Figure 2 is a top plan of the shoe after the molding operation.

Figure 3 is a part sectional view showing the operation of attaching the counter and 15 shank piece after the molding operation.

Figures 4 and 5 are detail sections on lines 4-4 of Figure 3 and 5-5 of Figure 1, respectively.

This invention relates to a modification of 20 the general method of making turn shoes, particularly described and claimed in my Patent No. 1,537,419, granted May 12, 1925, for turn shoes. The process as disclosed in this patent is as follows. The sole and upper 25 are assembled on the last wrong side out, the sole being in temper, and they are stitched together in the usual manner, the partially made shoe at this time being provided with neither a box toe nor a counter 30 stiffener. The last is then withdrawn from the shoe and the toe portion of the shoe turned, and in this condition a previously molded box toe may be inserted in the toe end of the shoe between the lining and the 35 cap of the vamp, the lower edges of the lining having been left unattached to the sole in the stitching operation to permit the cap to be inserted in position. If desired the toe 40 stiffener may be inserted after the sole has been allowed to dry. A previously molded counter stiffener assembled with a shank piece is then secured to the exposed heel end face of the sole, the shank thus extending forwardly of the heel seat, and the heel portion 45 of the shoe is then turned and the loose skirt of the lining is tucked and smoothed down inside of the counter stiffener so that this stiffener lies between the lining and the counter, and after the counter stiffener is 50 thus properly located a loose strip of the shank piece is turned down to overlap the inturned edges of the lining and the heel seat flange of the counter stiffener.

In the turning operation the shoe is more 55 or less wrinkled and marred, the sole being substantially flat and with a slight curvature upwardly at the toe end. While the sole is still in temper, according to the patented process, it is then molded as between 60 dies to finished form, particularly throughout its shank portion and its entire forepart. After the sole has been molded to form it is then permitted to dry and the subsequent operations are performed on the shoe while 65 it is dry.

The present invention covers a modification of this method in which instead of assembling the counter and shank piece in the shoe before the molding operation, as disclosed in the patent, this assembling operation is deferred until after the molding operation. This necessitates a modification in the form of the molding dies as is fully illustrated in Figure 1. The die 15 is the same as disclosed in the patent, but the 70 shank portion of the die 20 forming the inner face of the shoe is formed with a fairly sharp V-shaped extension which forms a decided depression in the inner face of the shank of the sole as shown at 22 in Figures 75 80 2 and 4.

After the molding operation the shoe is permitted to dry and the counter and shank piece are then assembled in position as illustrated in Figure 3. Preferably as is shown 85 in the patent the counter stiffener is one which has been previously molded and assembled with the shank piece 12, the shank piece having been split forwardly from the heel end so that after the counter is properly 90 located in place between the lining and counter, the loose strip 13 of the shank piece may be turned down so as to overlap the in-turned edges of the lining and the heel seat flange of the counter stiffener. While this 95 is the preferred construction of shank piece and counter stiffener, other constructions may be employed if desired.

This method is regarded as preferable to that in my patent because after the molding operation the shank of the sole conforms to the shank piece, whereas in the former method the shank piece and sole are not formed to fit each other when they are attached. It further has the advantage that when the counter and shank piece are being assembled, the anvil block 23 of the nailing machine being prolonged forwardly to underlie the entire shank and the rear portion of the forepart as shown at 100 24 so that while the nailing block 25 of the nailing machine through which the securing 105 nails are driven which attach the shank piece and counter in position is in clamping relation to the anvil piece, the extension 24 of this piece forms an anvil block against which a tack, as at 26, driven through the forward end of the shank piece and the sole 110 of the shoe may be clinched. This attaching 115 operation may thus be performed very readily by hand without requiring a separate handling of the shoe as is required where a special operation for this purpose is necessary as in the method described in 120 the patent. This modification also renders necessary one less operation while the sole of the shoe is in temper, thus expediting the 125 operations requiring the sole to be in this condition.

As herein shown the heel portion of the

shoe is turned back after the molding and drying operations and before the counter and shank piece are fixed in position, the heel portion of the shoe having been already 5 turned right side previous to the molding operation so that the counter and shank piece may be fixed to the upper face of the sole readily in the manner disclosed in the patent hereinbefore mentioned. This, however, is a very simple act since the upper only is manipulated, but if desired the counter and shank piece may be assembled while the heel portion is right side out according to 10 the method disclosed in my Patent No. 1,665,582, granted April 10, 1928, entitled Method of and machine for attaching counters to turn shoes.

Having thus described this invention it should be evident that various changes and 20 modifications may be made therein without departing from its spirit or scope as defined by the appended claims.

I claim:

1. A method of making turn shoes which 25 comprises securing an upper to a tempered sole both inside out on a last, removing the last, turning the shoe, molding the entire forepart and shank of the shoe sole while it is in temper to finished form with a depression to receive the shank stiffener, permitting the shoe to dry, fixing a shank stiffener in position in the depression of the sole, and then 30 relasting and completing the shoe.

2. The method of making turn shoes which 35 comprises securing an upper to a tempered sole both inside out on a last, removing the last, turning the shoe and inserting a previously molded toe stiffener into proper position in the toe, molding the entire forepart 40 and shank of the shoe sole while it is in temper to finished form with a depression to receive the shank stiffener, permitting the shoe to dry, fixing a previously molded counter and shank stiffener in position therein, and then relasting and completing the shoe.

3. A method of making turn shoes which 45 comprises securing an upper to a tempered sole both wrong side out on a last, removing the last, turning the shoe, molding the sole

under pressure to its final form with a depression to receive a shank stiffener, fixing a shank stiffener in said depression, and then finishing the shoe.

4. A method of making turn shoes which 50 comprises securing an upper to a tempered sole both wrong side out on a last, removing the last, turning the shoe, molding the sole under pressure to its final form with a depression to receive a shank stiffener, permitting the shoe to dry, fixing the shank stiffener in said depression, and then relasting and finishing the shoe.

5. A method of making turn shoes which 55 comprises securing an upper to a tempered sole both wrong side out on a last, removing the last, turning the shoe, molding the sole of the shoe while still in temper, fixing a shank stiffener in position, and then finishing the shoe.

6. A method of making turn shoes which 60 comprises securing an upper to a tempered sole both wrong side out on a last, removing the last, turning the shoe, molding the sole of the shoe while still in temper, allowing the shoe to dry, fixing a shank stiffener in 65 position, and then finishing the shoe.

7. The method of making turn shoes which 70 comprises securing an upper to a tempered sole both inside out on a last, removing the last, turning the shoe and inserting a previously molded toe stiffener into proper position in the toe, molding the entire forepart and shank of the shoe sole while it is in temper to finished form, permitting the shoe to dry, fixing a previously molded 75 counter and shank stiffener in position therein, and then relasting and completing the shoe.

8. A method of making turn shoes which 80 comprises securing an upper to a tempered sole both wrong side out on a last, removing the last, turning the shoe, molding the sole of the shoe while still in temper, fixing a shank stiffener in position, and then relasting and finishing the shoe.

In testimony whereof I have affixed my signature.

MILTON L. DODGE.
